APPARATUS FOR WASHING BEARINGS

William G. Merritt, Alameda, Calif.

Application August 11, 1945, Serial No. 610,371

6 Claims. (Cl. 134—116)

(Granted under the act of March 3, 1883, as amended April 30, 1928; 370 O. G. 757)

This invention relates to cleansing apparatus and particularly to apparatus for washing bearing assemblies.

An object of the invention is to provide an improved apparatus for automatically cleansing ball or roller bearing assemblies in an efficacious, rapid manner.

Other objects of the invention are to provide an improved cleansing apparatus for washing a plurality of ball or roller bearing assemblies simultaneously by forcing cleaning agent through the assemblies while rotating or oscillating the balls or rollers upon their axes so as to positively assure the dislodging of foreign matter and the thorough cleansing of said assemblies; to provide an improved apparatus for washing a bearing assembly wherein the bore of its inner race is closed with one of its races being held stationary and its other race is oscillated while a cleaning agent is forced between said races, whereby the bearing elements of said assembly are oscillated about their axes and intimately contacted by the cleaning agent so as to prevent damaging of said elements due to the lodging of foreign matter therebetween; to provide an improved apparatus of the character described having a resilient support for each bearing assembly adapted to be depressed for simultaneously actuating means for oscillating the assembly and for directing a solvent through said assembly so as to expedite the washing of the same; and to provide improved elements and arrangements thereof in a cleansing apparatus of the character described and for the purposes set forth.

In accomplishing these and other objects of the present invention, I have provided improved details of structure, the preferred form of which is illustrated in the accompanying drawings, wherein:

Fig. 1 is a side elevation, partly in section, of an apparatus for cleansing bearing assemblies and embodying the features of the present invention.

Fig. 2 is a transverse, vertical, sectional view, taken on the line 2—2 of Fig. 1.

Fig. 3 is a transverse, vertical, sectional view of one of the resiliently-mounted supports for receiving the bearing assemblies to be cleansed.

Fig. 4 is a plan view illustrating the relationship of the oscillating means.

Referring more in detail to the drawings:

In Fig. 1, the numeral 1 designates an upright, substantially rectangular standard or frame having a base 2 preferably supported upon casters 3 so as to be readily portable. A pair of parallel,

reinforcing posts or flat bars 4 and 5 are secured to the ends of the frame and extend vertically from the base 2 to a point above said frame. The upper ends of the vertical bars 4 and 5 are suitably connected by a flat, horizontal, cross bar 6, while a pair of similar cross bars 7 and 8 extend horizontally between the lower intermediate portions of said vertical bars. For reinforcing the upper bar 7 which is disposed in a horizontal plane, the lower bar 8 is arranged at a right angle to said bar 7 with its upper surface engaging the underside of the latter.

As shown in Figs. 1 and 2, the base 2 supports an electrical motor 9, a pump 10 operatively connected to the motor, and a reduction gear 11 which is driven by a small electric motor 12 supported thereon. A tubular manifold 13 communicates with the discharge of the pump 10 and projects upwardly and forwardly therefrom with a horizontal portion or leg 14 extending through and supported by the vertical end bars 4 and 5. The leg 14 of the manifold overlies the bar 7 in spaced, parallel relationship and has its free end plugged or otherwise closed as shown by the dotted line 15 (Fig. 1).

A rectangular tank or receptacle 16, having an open top and a flat bottom 17, is supported between the vertical bars 4 and 5 by the frame 1 and the manifold leg 14 extends longitudinally therethrough. The tank 16 is divided by a longitudinal wall or partition 18 to provide a filter compartment 19 (Fig. 2) which communicates with said tank through a suitable opening 20 formed in the lower portion of the partition adjacent one end thereof (Fig. 1). An angular tube or pipe 21 connects the opposite end of the filter compartment with the intake of the pump 10. Disposed transversely within the compartment 19 are a plurality of spaced, removable filter screens 22 which are slidably mounted between upright, parallel angle bars 23 and which are of progressively decreasing mesh.

A plurality of cylindrical bosses or nipples 24 depend vertically from the horizontal leg 14 of the manifold 13 in spaced, parallel relationship. As is clearly shown in Fig. 3, an upstanding, cylindrical nipple or collar 25, of greater length than the nipple 24, is screw-threaded within a circular opening 26 disposed diametrically of each nipple 24 so as to be in axial alignment therewith. A reciprocal support or rod 27 slidably engages within the nipple 24 and collar 25 so as to extend transversely through the manifold leg. The lower end of the rod depends from the nipple

through the tank bottom 17 to a point immediately above the cross bar 7 (Figs. 1 and 2).

For sealing off around the rod 27, an internal, annular groove or recess 28 is formed within the nipple 24 and receives a suitable packing ring 29. An enlarged, circular clutch element or disc 30 is secured to the lower end of the rod below the tank bottom 17 and said rod is constantly urged upwardly by a coiled or helical spring 31 so as to be resiliently supported. The latter is confined upon the rod in surrounding relationship between the tank bottom and a collar 32 which is removably connected to said rod above said tank bottom. A suitable thrust bearing 33 may be interposed between the spring 31 and collar 32.

For enclosing the spring, a cylindrical well or sleeve 34 projects upwardly from the tank bottom concentrically of the rod and a circular deflector plate or shield 35 is secured to said rod above the sleeve so as to overlie the same in closely-spaced relationship upon downward movement of the rod (Fig. 1).

An annular, upwardly-facing shoulder 36 for engaging the lower end of the collar 25 and providing valve means for closing the bore of said collar is formed on the rod 27 by enlarging the intermediate portion of said rod immediately below the collar. Above the shoulder 36, the upper portion of the rod is tubular to provide an axial bore 37 which is adapted to communicate with the interior of the manifold leg 14 through a plurality of radial openings or ports 38 upon downward movement of said rod. Due to the provision of the spring 31 which constantly urges the rod upwardly, the shoulder 36 is normally held in engagement with the lower end of the collar 25 and the ports 38 are disposed within said collar so as to be out of communication with the manifold leg. A packing ring 39, similar to the ring 29 of the nipple 24, engages within an annular groove or recess 40 formed in the bore of the collar for sealing off around the tubular portion of the rod.

Mounted upon the upper extremity of the rod is an enlarged circular supporting plate or head 41 having an outwardly and upwardly flared or dished seat 42 formed in its upper surface and an axial bore 43 communicating with the bore 37 of said rod. As is clearly shown in Fig. 1, a bearing assembly 44 is adapted to be supported upon the seat 42 for cleansing purposes and may be of the roller or ball type. The latter type is illustrated and includes a plurality of balls 45 confined between an inner annular race 46 and an outer annular race 47.

For lowering the rods 27 so as to move the ports 38 into registration with the manifold leg 14, a cylinder 48 is mounted upon the upper cross bar 6 in axial alignment with each rod and has a non-rotatable plunger 49 depending from its piston (not shown) so as to undergo reciprocation relative to the rod (Fig. 1). Such reciprocation is controlled by a two-way valve assembly 50 supported by the cross bar and having connection with the upper and lower ends of the cylinder 48. For engaging within and closing the bore of the inner bearing race 46 upon downward reciprocation of the plunger 49, a conical tip 51 is mounted on the lower end of said plunger (Fig. 1). The engagement of the plunger tip with the inner race axially aligns the bearing assembly 44 and clamps its outer race 47 against the dished seat 42 of the head 41, whereby external communication with the rod bore 37 is established by the spaces be-

tween the balls 45 and races of said assembly. A circular plate or hood 52, having an external depending skirt 53, is carried by the plunger above and in concentric relation to the tip 51 so as to closely overlie the bearing assembly upon lowering of said plunger. The hood 52 is preferably formed of transparent plastic material and serves to deflect fluids passing through the bearing assembly downwardly into the tank 16.

A circular clutch element or plate 54 underlies the disc 30 of each rod 27 in axial alignment therewith and is rotatably supported by the cross bar 7 by means of an integral depending pin 55 which engages within an opening formed in said bar. As is clearly shown in Fig. 1, a collar or bushing 56 is preferably mounted within the opening for receiving the pin 55 and a layer 57 of fibrous material, such as brake lining, is preferably secured to the upper surface of the plate 54 (Fig. 4). The disc 30 is adapted to engage the plate upon lowering of the rod, whereby rotation of said plate is transmitted to said rod. A radial arm 58 projects forwardly from each plate and the outer end of the arm is pivotally connected to the outer ends of the arms of adjacent plates by suitable links 59 (Fig. 4), whereby said plates may be rotated or oscillated about their axes simultaneously.

For accomplishing simultaneous oscillation of the clutch plates, a connecting rod 60 extends from one end of one of the links 59 to a vertical bell crank 61 pivotally supported by an angular bracket 62 which is fastened to the cross bar 7 (Fig. 2). Self-centering or rod end bearings 63 are carried by the ends of the rod 60 for pivotally connecting the same to the link end and the bell crank. One arm of the bell crank 61 is directed upwardly and has an elongated slot 64 (Fig. 1) formed therein for adjustably receiving a screw 65 upon which one of the rod bearings 63 is confined by means of suitable nuts, whereby the stroke of the rod may be varied upon longitudinal adjustment of the screw relative to the slot. A pitman 66 pivotally connects the other arm of the bell crank to a crank 67 which is carried and rotated by the reduction gear 11.

Due to the foregoing arrangement, the plates 54 are constantly oscillated about their axes and the rods 27 are similarly oscillated when lowered so as to engage their discs 30 with said plates. Since a separate valve assembly 50 is provided for each cylinder 48 and its plunger 49, the rods 27 may be lowered and oscillated independently by individual actuation of the plungers. The oscillation of the rods is transmitted to the outer races 47 of the bearing assemblies 44 through the heads 41 which are engaged by said races, thereby causing the balls 45 to rotate upon their respective axes. Since the tips 51 of the non-rotatable plungers engage within the bores of the inner races 46, the latter remain stationary during oscillation of the outer races and rotation of the balls.

Operation

The operation of a cleansing apparatus constructed as described herein is as follows:

A suitable solvent, such as hot oil, is placed in the tank 16 so as to be drawn through the filter compartment 19 by the pump 10 and forced into the manifold 13 and the leg 14 thereof. In order to cleanse the bearing assembly 44, the same is supported upon the head 41 of one of the rods 27 as shown in Fig. 1. The plunger 49 which overlies the rod is then lowered by manipulating

the proper valve assembly 50 so as to direct air under pressure to the upper end of its cylinder 48, whereby the tip 51 of said plunger engages within the bore of the inner race 46 of said assembly so as to clamp its outer race 47 against the seat 42 of the head. Continued lowering of the plunger, moves the rod 27 downwardly until its disc 30 contacts the oscillating plate 54 therebelow, thereby lowering the ports 38 of said rod into communication with the manifold leg 14. Due to the constant oscillation of the plate 54, the rod, its head and the outer race of the bearing assembly are oscillated while the inner race remains stationary so as to rotate the balls 45 back and forth upon their axes.

The solvent within the manifold leg, being under pressure, enters the ports 38 and is directed upwardly through the bores 37 and 43 of the rod and head, respectively. Since the plunger tip 51 closes the bore of the inner bearing race and the outer bearing race is clamped against the seat 42, the solvent is forced to flow through the space between said races in intimate contact with the balls. It is readily apparent that the simultaneous flow of the solvent and the rotation of the balls exposes the entire surface of each ball to said solvent so as to thoroughly cleanse the same. Also, the back and forth rotation of the balls tends to dislodge grit, minute particles or other foreign matter and prevents marring or damaging of said balls.

After passing through the bearing assembly, the solvent strikes the transparent hood 52 and is deflected downwardly by its skirt 53 into the tank 16. Since the deflector 35 overlies the sleeve 34 and is lowered into close proximity with the upper end thereof upon downward movement of the rod, the solvent is prevented from entering said sleeve and escaping through the lower end of the same. The suction of the pump 10 draws the solvent within the tank through the opening 20 formed in the partition 18 into the filter compartment 19, longitudinally of said compartment through the screens 22 and then through the angular pipe 21. From the pump, the solvent is forced into the manifold 13 and maintained under pressure therein so as to provide a constant supply.

When the bearing assembly has been thoroughly cleansed, the valve assembly 50 is again manipulated so as to reverse the flow of air from the upper to the lower end of the cylinder 48 and thereby retract or raise the plunger so as to move its tip 51 out of engagement with the inner bearing race. Since the spring 31 is constantly urging the rod upwardly, its tension lifts said rod upon such disengagement. At the same time, the disc 30 of the rod is raised out of contact with the plate 54 so as to cease oscillation of said rod, its head and the outer bearing race, while the shoulder 36 of the rod is moved upwardly into engagement with the lower end of the collar 25 to dispose the ports 38 within the bore of said collar and seal the same against communication with the manifold leg. The bearing assembly may now be removed from the head and another assembly supported thereupon for cleansing as described hereinbefore. Of course, a plurality of bearing assemblies may be cleansed simultaneously by supporting an assembly upon each head in the manner described.

While I have shown but one embodiment of my invention, it is susceptible to modification without departing from the spirit of the invention. I do not wish, therefore, to be limited by

the disclosures set forth, but only by the scope of the appended claims.

The invention described herein may be manufactured and used by or for the Government of the United States of America for governmental purposes without the payment of any royalties thereon or therefor.

I claim:

1. An apparatus for cleansing bearing assemblies including, a tubular manifold, means for supplying a solvent under pressure to the manifold, a plurality of reciprocal rods extending transversely through the manifold, resilient means for urging the rods upwardly, means for limiting the upward movement of said rods, the upper end of each rod having a bore therein, said rod having ports therein above the interior of the manifold so as to establish communication between the bore and said manifold upon downward movement of the rod, means at the upper end of each rod for supporting a bearing assembly having concentric races, a plunger adapted to be lowered into engagement with each bearing assembly so as to clamp the same against the supporting means, the bore of the bearing assembly being closed by the plunger and the rod being forced downwardly by the lowering of the plunger, whereby the ports are moved into communication with the manifold to direct the solvent upwardly through the bore and between the races of said bearing assembly, an enlargement at the lower extremity of each rod, and oscillating means adapted to be engaged by the enlargement upon downward movement of said rod, whereby the outer race of each bearing assembly is oscillated while its inner race remains stationary and solvent is directed between said races.

2. An apparatus for cleansing bearing assemblies including, a tubular manifold, means for supplying a solvent under pressure to the manifold, a plurality of reciprocal rods extending transversely through the manifold, resilient means for urging the rods upwardly, means for limiting the upward movement of said rods, the upper end of each rod having a bore therein, said rod having ports therein above the interior of the manifold so as to establish communication between the bore and said manifold upon downward movement of the rod, means at the upper end of each rod for supporting a bearing assembly having concentric races, a plunger adapted to be lowered into engagement with each bearing assembly so as to clamp the same against the supporting means, the bore of the bearing assembly being closed by the plunger and the rod being forced downwardly by the lowering of the plunger, whereby the ports are moved into communication with the manifold to direct the solvent upwardly through the bore and between the races of said bearing assembly, and means for oscillating each rod upon such downward movement thereof so as to simultaneously oscillate the outer race of each assembly.

3. An apparatus for cleansing bearing assemblies including a plurality of resiliently-mounted rods, the upper end of each rod having a longitudinal bore, means at the upper end of each rod for supporting a bearing assembly having concentric races, means for closing the bore of each bearing assembly and depressing its supporting rod, means for forcing a solvent through the bore of the rod so as to direct the same between the races of the bearing assembly upon downward movement of said rod, and means for oscillating each rod so as to oscillate a part of said

bearing assembly upon such downward movement.

4. An apparatus for cleansing bearing assemblies including, a plurality of resiliently-mounted rods, the upper end of each rod having a longitudinal bore, means at the upper end of each rod for supporting a bearing assembly having concentric races, means for engaging each bearing assembly so as to confine the same upon its supporting means and depress its rod, valve means operable by such depressing for directing a solvent into the bore of each rod and through the bearing assembly, and means for oscillating each rod so as to oscillate a part of said bearing assembly upon the depressing of the same.

5. An apparatus for cleansing a bearing assembly having annular races including, a vertically movable support for the bearing assembly, the support having means for directing fluid through said assembly, means for oscillating said support so as to oscillate one race of said assembly relative to the other race, the fluid directing means and oscillating means being operable in response to vertical movement of said support, and means for moving said support vertically.

6. A bearing assembly cleansing apparatus including, a vertically movable support adapted to receive a bearing assembly, means for engag-

ing and confining the bearing assembly upon the support, said support being moved vertically by the assembly engaging means and having means for directing a cleaning solvent through said assembly, means operable by said support upon vertical movement thereof for placing said solvent directing means in fluid connection with a source of solvent, means for oscillating a part of the assembly, and means operable by said support upon vertical movement thereof for engaging said oscillating means simultaneously with the connection of said solvent directing means with said source of solvent.
